UNITED STATES PATENT OFFICE.

ABRAHAM QUINN, OF NEW YORK, N. Y.

IMPROVEMENT IN APPARATUS FOR DISTILLING PETROLEUM AND OTHER OILS.

Specification forming part of Letters Patent No. 36,481, dated September 16, 1862.

To all whom it may concern:

Be it known that I, ABRAHAM QUINN, of the city, county, and State of New York, have invented certain new and useful Improvements in Apparatus for Distilling Oils and other Substances; and I do hereby declare that the following is a full, clear, and exact description of the same, reference being had to the accompanying drawings, forming part of this specification, in which—

Figure 1 is an elevation, partly in section, of an apparatus with the improvements applied. Fig. 2 exhibits a sectional view of a modification of part of the apparatus.

Similar letters of reference indicate corresponding parts in the two figures.

This invention consists in an improvement in the rectifier which constitutes the subject-matter of my Letters Patent dated April 9, 1861; also, in an improved purifier combined with such rectifier; and, further, in an improved arrangement of one or more such rectifiers and mode of applying the oil to the rectifiers and the retort, by which several improvements, besides accomplishing all that is accomplished by my above-described rectifier, I am enabled, first, to supply the still continuously with oil freed from water or explosive vapors during the process of distillation; second, to cause a continual stream of oil to run from separate condensing-chambers after having been completely rectified and agitated in contact with chemicals while distilling and condensing; third, to distill oils at the lowest heat necessary to convert them into vapor, and so lessening the quantity of permanent gas produced in the distilling process; fourth, to cause the vapor of the heavier oils on their way toward the condensing apparatus to meet the crude oils on their way to the still, and so to heat the latter oil to such an extent as to extract the vapor of the lighter oils; and, fifth, to extract from crude petroleum or coal-oil all of the products which are best suited for illuminating purposes and leave a more unctuous oil for lubricating or other purposes.

To enable others skilled in the art to make and use my invention, I will proceed to describe its construction and its operation in the distillation of crude petroleum or coal-oil.

A is the retort of the still, having its bottom nearly flat inside, so that an alloy composed of tin and lead, when in a state of fu-

sion, may spread thinly over it to prevent the residuum of distillation from burning, and facilitate the cleaning of the retort when the heavy ores are distilled to dryness.

B is the neck of a *D*-shaped transverse section, like an ordinary coal-gas retort, its bottom being flat, so that the oil will flow over in a thin sheet, and the flue *Z* of the furnace surrounding it to keep it heated. On the bottom of the neck *B* there are two dams, *a* and *y*, which will be hereinafter described.

C P Q is one of my improved rectifiers, connected with the still-neck *B*; and *C' P' Q'* is another of such rectifiers, arranged in a higher position and connected with *C P Q*. These rectifiers, instead of being composed of simple inverted siphons, like that which constitutes the subject of my Letters Patent herein-before referred to, are composed each of an outer close vessel, *C* or *C'*, an inner open pan, *P* or *P'*, and a pipe, *Q* or *Q'*, which corresponds with the overflow-pipe *F* of that rectifier. The pans *P P'*, which constitute the principal feature of novelty in these rectifiers, serve the two purposes of enabling the processes of distilling and rectifying to be made continuous and of containing chemicals in a liquid form for the purification of the oils; and to facilitate the latter operation they are furnished with perforated diaphragms *p p p' p' p'*, arranged one above another, to cause the oil to mingle with and be detained as it ascends through the chemical solution.

D Q² is a rectifier like that which forms the subject of my before-mentioned Letters Patent, but fitted with perforated diaphragms *p² p'*, to detain the oil as it ascends through the chemical solution in the bottom of the vessel *D*. The vessel *D* is arranged higher than *C*, but connected with the top of it by a large pipe, *D^x*, and *C* is connected with the top of *C* by a large pipe, *C^x*, and the vessel *C* is connected with the neck *B* of the retort. The rectifier *D Q²* is entered at the top by a small pipe, *g²*, for the introduction of the crude oil from the receiver *H H*, said pipe descending to the bottom of the vessel *D* below the perforated diaphragms, and from the upper part of the vessel *D* there leads a similar pipe, *g'*, which enters the top of the vessel *C* and descends nearly to the bottom of its pan *P'*, and the vessel *C* is connected with the pan *P* by a similar pipe, *g*. From near the top of the pan

P a pipe, y' , leads into the neck B of the retort to convey oil into it, said pipe entering it beyond the dam y , and from the said neck B, between the dams a and y , a pipe, b , leads through the dam a into the retort, for the purpose of conveying the heavier oil thereinto at a point near the bottom thereof. The lower parts of the vessels C C' below the pans P P' constitute condensers for the heavier portions of the oil, and these and the lower part of D are surrounded by cold-water tanks K K K.

E Q³ is a purifier, in which the naphtha or most volatile portions or products of the oil are purified with a weak chemical solution at low heat, said purifier being essentially like my patented inverted-siphon rectifier, and being arranged in a more elevated position than the rectifier D Q². The principal portion E of this purifier is connected at its upper part with the upper part of the vessel D by means of a pipe, E¹, which descends nearly to the bottom of E, where it is fitted with a perforated diaphragm, p³, to cause the detention of the naphtha or other product in the chemical solution; and the upper part of E is connected by a pipe, F², with a leader, F³, with which is connected a pipe, F', running through the water-tank or condenser F, for the condensation of the lighter oils, the said pipe F' having the form of a worm within the said tank. The cold water is introduced constantly to the condenser by the pipe J, and overflows at the top of the elevated pipe M, which is provided with a faucet, M', to permit the water to flow from it down the pipe S to the crude-oil receiver H, for the purpose of forcing the oil from the said receiver up the pipe U to the pipe g, before mentioned, by which it is conveyed into the vessel D. This receiver H has in its interior a tank, I, for the reception of the residuum of the chemicals employed for purification. This tank is connected at its mouth with the top of the receiver by means of perforated diaphragms T, and the pipe S delivers the water above these perforated diaphragms, so that it may produce a mingling and agitation together of the chemicals and the oil as the latter is caused to rise into the pipe U by the subsidence of the water in the receiver H, the oil always floating on the water and being forced up by it, owing to the greater specific gravity of the latter.

V is a well connected with the pipe U for the separation and reception of any water that may pass up the said pipe with the oil. The receiver H has the oil supplied to it by a funnel, O, the mouth of which should be level with the floor, that the barrels may be rolled up to it and have their contents poured directly into it.

L L' L² are leaders to convey the different kinds of oil obtained by the distillation to the separate receivers provided for them, and l l' l² are faucets for drawing off the oil from the vessels C and C' and worm F.

L* is a leader for conveying the residuum of the chemical matters to the tank I. This leader is provided with a funnel, G, into which

such residuum is drawn from the vessel D by a faucet, h², and the residuum from the pans P P', after having been first drawn off into the bottoms of the vessels C C' by faucets h h', is drawn off from the latter by the faucets l l' into buckets, and from thence transferred into the funnel G. X X' are elevated leaders like the hydraulic mains of gas-works, and m m' are pipes leading from the bottoms of the vessels C C' into said leaders. 3 4 5 6 7 8 9 are gage-cocks to enable the depth of oil in the several parts of the apparatus to be ascertained.

Having now described the principal parts of my improved apparatus, I will proceed to describe the manner in which the process of distillation and rectification are performed in it. I will first suppose all the faucets attached to the apparatus to be closed. I open the faucet M' to allow some water to run from the overflow-pipe M of the cold-water tank F into the receiver H to prevent oil from running into the siphon N, after which I open the faucet of the funnel O and empty the barrels of crude oil directly thereinto. When the receiver has been thus filled with oil, I close the faucet of O. The basins P P', chamber D, and purifier E are then filled to a suitable depth with chemical solutions of different strengths, according to the heat employed and gravity of the oils, such solutions being run with funnels of the pipes Q Q' Q² Q³, which combine with the said basins, chamber, and purifier to form inverted siphons.

Instead of the chemicals being introduced to the pans P P' in a liquid form, they may be introduced in a dry state in cages through man-holes R R in the vessels C C', or small lumps may be placed on gridirons in the upper parts of the pans, chamber, and basin to purify the oil while in a state of vapor. The chemicals used may be of any suitable kind, but generally are either alkaline or acid. A portion of water is next run into the retort A through the faucet R' sufficient to make steam to warm the rectifiers and purifier, and the chemicals contained therein, and fire is kindled in the furnace below it, and when the apparatus is sufficiently heated I open the faucet M' to permit water to descend through the pipe S and up through the strainers T, where it mixes with the hot chemical residuum and is agitated with the oil. The crude oil, being lighter than the water, ascends in the pipe U, at the top of which any water that may have been carried up with it settles in the well V, and from thence the said oil flows down through the pipe g² into the chamber D, thence through the pipe g', pan P', pipe g, and pan P, entering the said chamber and pans at the bottom, and ascending through the perforated diaphragms p² p³, p' p', and p p. From the pan P it passes off through the pipe y' under the dam y, and along the flat bottom of the still-neck B, where it is exposed to the heat of the chimney-flue Z, and through the dam a and pipe b into the body of the still. The oil is represented in the drawings of a yellow

color, the chemicals red, and the water blue. As the oil flows into the chamber O its lighter portions evaporate and pass over through the pipe E^x into the chamber E, and are purified by forcing themselves through and agitating themselves among the chemical solution in said chamber, from whence the lightest portion passes to the worm-pipe F', to be condensed, leaving behind in the chamber E the less light portions to be further agitated with the chemical solution, and as the oil accumulates in E it runs out by the siphon-pipe d into the chamber D to be rectified, and so on, the operation proceeding in a similar manner through the whole series of rectifiers and the still, the vapors passing upward through the pipes B C^x D^x E^x and being condensed in the vessels C' C' D' E' or worm F', according to their specific gravity. The faucets l l' are left open to allow the paraffine and illuminating oils to run off to their separate receivers. When it is desired to have the oils condense, rectify, come in contact with chemicals, or to increase the heat farther up the series of rectifiers and chambers, the distilled oils may be retained in the lower part of one or other of the vessels C C' by closing the faucets l l' and opening faucets l* l* higher up the pipes m m', or by pouring waste water into the siphons f f', attached to the pipes m m'. It may be observed that it is impossible for water to get into the still by reason of the overflow to the vessels K K K, provided for the pipes Q Q' Q². In case the outlet of the pipe b gets choked with tarry residue, the oil running into the retort A flows over the dam a toward the retort, and when it rises in the retort above the level of the dam a it is prevented from running back into the vessel C by the higher dam y and causes the oil in the basin P to rise sufficiently to increase the pressure against the lighter oils descending in the tubes g g' g², and cause the supply to stop running till it falls again by evaporation. It is necessary to leave height enough in the tubes Q Q' Q² Q³ to allow the chemical solutions to rise and fall; and, accordingly, when the oil rises, as described, it will cause the water in the pipe S to overflow, as it will also do when all the crude oil has left the receiver H. A wooden stick may be employed to clear the tube b, and to know the exact depth of oil in the retort A, by running it down for a moment through the cock R, and the little vapor that escapes in so doing emanates from the heavy oils and will not be liable to explode in case a spark of fire comes in contact, as all the lighter vapors pass off prior to the oil entering the retort A. Fresh chemical solutions are supplied, without impeding the process of distillation, by first running a portion of the residue out of the faucets h h' h² and introducing the fresh by the pipes Q Q', running the residue into the tank I. The hot vapor passing from the still over the oil-surface in the basin P will obviate the liability to foam over, and in case the vapor might

condense to excess on said surface the basins may be covered over like P', having merely a small outlet at the top for the escape of vapor. When all the crude oil has left the receiver H H, I close the faucet M', to prevent the water from running into the pipe S, and while the receiver is being refilled the water is run off by the siphon-faucet N. The receiver H H and tank I are emptied of water and residue, when desired, by opening faucets k and j, and while the receiver is being refilled with petroleum the heavy oil in the retort A may be partly run down, and its vapor condensed in the lower parts of the vessels C C', and is prevented from condensing in the pipe F' or worm by running the water out of either one of the gas-leaders X X', allowing the gas to have free vent in ascending the pipe m or m', and regulating the gravity of the distilled oils, as desired, till the crude oil is ready to be run off by the retort A, as before described.

In the process of distilling by this apparatus the oil, entering the apparatus at the pipe g² and moving continuously toward the still, has its lighter portions evaporated by the heat carried off by the vapors of the heavier portions, which are passing from the still in the opposite direction, and hence a great economy of heat is obtained, which is one of the great advantages of my invention. The process may be continued day and night without interruption for the six working days of the week, distilling the paraffine-oils to dryness, and the apparatus having been cooled off in the interval between Saturday night and Monday morning can be cleaned out for a fresh operation.

In large refineries several stills for distilling one kind of oil with the one kind of chemical and with their appendages, like Fig. 1, can be attached to the same leaders, like L, L', L², X, X', and F', so that the one worm and water-tank, F', will be sufficient for the whole.

Oils that are not likely to foam may be distilled and condensed in a retort constructed as represented in Fig. 2, to allow the vapor to pass underneath the basin or rectifier to be condensed, and its lighter portions to ascend in the pipe a* and pass into the next rectifier. What I claim as my invention, and desire to secure by Letters Patent, is—

1. The still-neck B, constructed with dams y y, and having pipes b and y', applied in combination with such dams, substantially as herein specified.
2. The basins P P', placed within the chambers C C' of the rectifiers, and in combination with the pipes Q Q', substantially as herein specified.
3. The perforated diaphragms p p' p' p² p², arranged within the rectifiers, substantially as and for the purpose herein described.
4. The arrangement of several rectifiers in combination with each other, with the still-retort, and with the device or apparatus for feeding the crude oil in such manner that the vapors of the heavier oils on their way to the

condensing apparatus meet the crude oil on its way toward the still-retort and heat the latter oil to such an extent as to extract the vapor of the more volatile portions of it before it arrives at the retort of the still, substantially as herein specified.

5. The purifier E, arranged in relation to the rectifiers, the feeding apparatus, and the worm F', substantially as and for the purpose herein specified.

6. The oil-receiver H and chemical-tank I and their pipes S U, funnel O, siphon N, cocks j k, and strainers T T, the whole combined to operate substantially as herein specified.

ABRAHAM QUINN.
